STEP-BY-STEP COMBINATION DOOR
LOCKING MECHANISM

John J. Dury, Montreal, Quebec, Canada

Application January 10, 1948, Serial No. 1,630
In Canada January 17, 1947

4 Claims. (Cl. 70—313)

1

This invention relates to burglar baffling door locks and has for its principal object the provision of an efficient, economical, and thoroughly practical door locking and releasing mechanism of the pushbutton-controlled combination type which cannot be operated to unlock the door from the outside except by actuating certain of the controlling pushbuttons in a predetermined sequence. A further object is to provide, in a door locking and releasing mechanism of the type referred to, novel arrangements whereby the door may be unlocked from the inside independently of the pushbuttons.

A salient feature of the invention consists in the provision of a door locking and releasing mechanism comprising a movable door locking bolt, a pair of vertically movable slides including a bolt controlling slide and a pawl releasing slide, a retaining pawl for supporting the bolt controlling slide in different elevated positions to which said slide is successively raised, a series of pushbuttons, and slide actuating elements connected to said pushbuttons and cooperating with portions of said slides to (a) effect a step-by-step raising of the bolt controlling slide to a bolt releasing or retracting position in response to successive operation of certain of said pushbuttons in a predetermined sequence; or (b) raise the pawl releasing slide against said pawl and thereby withdraw the pawl from supporting engagement with the bolt controlling slide in response to operation of the pushbuttons in other than said predetermined sequence.

Another feature of the invention consists in the provision of novel arrangements whereby either an adult or a small child may operate the bolt controlling slide to a bolt releasing or retracting position to unlock the door from the inside or outside without disturbing the initial setting of the pushbuttons and the pawl releasing slide.

Other objects, advantages and characteristic features of the invention will be set forth or made apparent in the following detailed description of the accompanying drawings, in which—

Fig. 1 is a side elevational view of a portion of a door and door jamb to which component parts of my improved door locking mechanism are applied.

Fig. 2 is a view similar to Fig. 1 but with the door handle and a cover plate of the door locking mechanism removed to disclose parts that would otherwise be concealed from view.

Fig. 3 is a sectional view taken substantially along the section line 3—3 of Fig. 2.

2

Fig. 4 is a sectional view taken substantially along the section line 4—4 of Fig. 2.

Fig. 5 is a sectional view taken substantially along the line 5—5 of Fig. 2.

Figs. 6 to 9 inclusive are diagrammatic views showing the manner in which the bolt controlling slide is raised to a bolt releasing or retracting position by the pushbuttons when the latter are operated successively in the correct sequence.

Fig. 10 is a diagrammatic view showing the manner in which the pawl, which supports the bolt controlling slide in its different positions of elevation, is released from supporting engagement with said slide by an upward pawl releasing movement of the pawl releasing slide when the pushbuttons are operated in other than the correct predetermined sequence.

Fig. 11 is a view similar to Fig. 4 but showing the parts in a different position.

In these drawings, 5 and 6 designate, respectively, a door and a door jamb to which component parts of my improved combination door lock are applied.

The part of the lock carried by door jamb 6 comprises a vertically disposed bolt-engaging pin 7 rigidly mounted in a corner recess 8 by means of vertically spaced supporting brackets 9.

The remaining parts of the lock carried by door 5 include a pivotally mounted jaw-type bolt 10 and bolt locking and releasing mechanisms generally indicated at 11.

Bolt 10 operates in recess 12 of door 5 and is mounted to swing about vertical pivot 13 carried by angle plate 14 countersunk in said recess. Plate 14 is provided with a slot 15 accommodating bolt 10 and the ends of pivot 13 are fitted in openings provided in portions of the plate located above and below said slot. Bolt 10 is formed with two integral jaws 16 adapted to be disposed in embracing engagement with the bolt-engaging pin 7 of door jamb 6 as shown in Figs. 2 and 3. Bolt 10 is also provided with a tail extension 17 affording a locking shoulder 18 adapted to be engaged by a locking pin 19 to thereby lock the bolt in the position shown in Fig. 3 and prevent opening of the door 5.

Locking pin 19 works in guide bore 20 provided in plate 14. Bore 20 extends downwardly from the upper edge of plate 14 and intersects a narrow portion 15a of slot 15 through which the tail extension 17 of bolt 10 travels when said bolt is free to swing in the door releasing direction indicated by arrow 21 in Fig. 3.

Door 5 is an inwardly opening door which is locked in closed position when jaws 16 of bolt 10

are engaged with pin 7 as shown in Fig. 3 and the locking pin 19 is disposed in its lowermost bolt-locking position (Fig. 4) to serve as a bolt stop cooperating with the shoulder 18 of bolt 10 to hold the tail extension 17 of the bolt against swinging movement in the door releasing direction indicated by arrow 21.

Three different arrangements are provided for operating the locking pin 19 to a bolt releasing position to permit opening of the door 5. One arrangement includes a pushbutton 23 projecting upwardly through an opening 24 provided in the upper hollow end portion 25a of a handle member 25 rigidly secured to the inner side of door 5. The lower end of pushbutton 23 bears against one end of a lever 26 intermediately pivoted at 27. The other end of lever 26 extends into a vertical elongated slot 28 provided in an upper part of locking pin 19 which projects above plate 14.

When pushbutton 23 is depressed it operates lever 26 to raise the lower end of locking pin 19 above the tail extension 17 of bolt 10. This permits bolt 10 to swing in the door releasing direction indicated by arrow 21 when door 5 is swung inwardly by pulling on the handle member 25. During the inward movement of the door, the pressure of pin 7 against the outer jaw 16 of bolt 10 causes the bolt to swing about the pivot 13 so that jaws 16 are withdrawn from engagement with bolt-engaging pin 7 by a combined sliding and angular movement of the jaws relative to said pin.

A second arrangement for unlocking door 5 from the inside comprises a pusher pin 29 working in that portion of bore 20 which extends below bolt 10. The upper end of pin 29 is engaged by the lower end of locking pin 19 when the latter is in the bolt locking position shown in Fig. 4. The lower end of pin 29 is engaged and supported by an operating cam 30 rotatably mounted in a bore 31 intersecting the lower end of bore 20. Cam 30 is shown as a generally cylindrical member which is recessed as indicated at 31a to provide a cam-lift portion 32, one end of member 30 being extended inwardly beyond the inner side of the door and shaped to provide an operating handle 33. Cam 30 is normally arranged with the recess 31a facing upwardly and receiving therein the lower end of pusher pin 29.

The lower end of locking pin 19 is formed with an inclined or bevelled surface 33a which faces toward the shoulder 18 of locking bolt 10 but is positioned below said shoulder when the locking pin is in the lowered bolt-locking position shown in Fig. 4. When cam 30 is turned through a half revolution from the position shown in Fig. 4 the cam lift portion 32 raises pusher pin 29 and locking pin 19 to the position shown in Fig. 11. In this position of locking pin 19 the bevelled surface 33a of the locking pin is disposed opposite the shoulder 18 of the locking bolt. This permits door 5 to be readily opened by pulling inwardly on handle member 25 or by pushing from outside since surface 33a of locking pin 19 provides an inclined plane against which shoulder 18 acts to force the locking pin upwardly against spring 48 to a bolt releasing position when torque is applied to the locking bolt 10 by the pressure which pin 7 exerts against the outer jaw 16 in response to the inward pull on handle 25. This second arrangement for unlocking the door from the inside is for the convenience of children unable to reach and operate the push pin 23 at the top of handle 25.

The third arrangement for unlocking the door is operable from the outside and is of the push-button-controlled combination type which functions only when certain of the controlling push-buttons are operated in a predetermined sequence. The principal components of this third arrangement include a lock releasing lever 35 which operates locking pin 19, a lock releasing slide 36 which operates lever 35, a retaining pawl 37 which cooperates with teeth 38 on slide 36 to hold said slide in different elevated positions to which it is progressively shifted in a lock releasing direction, a resetting or pawl releasing slide 39 which cooperates with pawl 37 to reset the locking releasing slide 36 when the control push-buttons are operated in incorrect sequence, a plurality of slide actuating elements 40, and a plurality of control pushbuttons 41 to which the elements 40 are operatively connected.

One end of slide releasing lever 35 extends through guideway 44 (Fig. 2) of plate 14 into slot 45 provided in the intermediate portion of locking pin 19. The other end of lever 35 is pivoted, at 46, to a supporting bracket 47. Lever 35 is urged downwardly by a biasing spring 48 having its upper end secured to the lever and its lower end fastened to an anchoring pin 49.

Lock releasing slide 36 is recessed at 51 to accommodate lever 35 and to provide a lever operating shoulder 52. When slide 36 is shifted to the upper limit of its travel, as hereinafter described, the shoulder 52 operates lever 35 against the resistance of spring 48 to lift locking pin 19 to a bolt releasing position above the tail extension 17 of bolt 10.

The slides 36 and 39 are guided by suitable brackets 54 and 55 and are arranged in abutting edge to edge relation so that their corresponding side surfaces are co-planar as shown in Fig. 3. The pawl 37 is shown as a vertically disposed substantially triangular member having one lower corner portion fastened to bracket 54 by pivot 51 so that the remaining lower corner portion bears against the upper end of slide 39. The upper corner portion of pawl 37 is shaped to provide a tooth 58 which bears against the toothed portion of slide 36.

The abutting edges of slides 36 and 39 are notched to provide notches N¹, N², N³, N⁴, N⁵, and N⁶ in slide 39 and similar notches N⁷, N⁸, N⁹ and N¹⁰ in slide 36.

Each of the slide actuating elements 40 is provided, at one end, with a laterally extending slide actuating projection 60 which normally lies within one of the previously mentioned notches of slide 39. The other end of each element 40 is formed into a fork which is fastened, by pivot 61, to the inner end of the stem portion 62 of one of the pushbuttons 41.

The pushbuttons 41 and their stem portions 62 are slidably mounted in guide openings 63 provided in a guide block 64 to which the slide guiding brackets 54 and 55 are fastened. Biasing springs 65, encircling the stem portion 62, normally serve to hold the pushbuttons in the projected portions shown in Fig. 5.

The locking pin operating lever 35, the slides 36 and 39, the pawl 37, the slide actuating elements 40 and the pushbuttons 41 are normally positioned as shown in Fig. 5 with the bolt 10 held in door locking engagement with bolt-engaging pin 7 of door jamb 6 by the locking pin 19. In this position of the parts the door can be unlocked from the outside only by operating certain of the pushbuttons 41 in a predetermined sequence

to effect a progressive or step by step elevation of slide 36 to its uppermost position and thereby cause shoulder 52 of said slide to operate lever 35 and locking pin 19 to a bolt releasing position. In this connection it will be noted that, in the normal position of slides 36 and 39, the notch N⁸ of slide 36 is positioned opposite the notch N⁴ of slide 39 and that the remaining notches of slide 39 are opposed to and closed by straight portions of the abutting edges of slide 36. It will also be noted that distinguishing reference letters A, B, C, D, E and F have been applied to the push-buttons for convenient reference in describing the sequential operation of the buttons necessary to unlock the door from the outside.

In the present instance, the slides 36 and 39 are notched so that the order in which the push-buttons must be operated to unlock the door is D—B—E—D, hereinafter referred to as the correct sequence or combination.

When pushbutton D and its attached slide operating element 40 are shifted from the position shown in Fig. 5 to the position shown in Fig. 6, the projection 60 of said element passes from notch N⁴ of slide 39 into notch N⁸ of slide 36 and operates against the top of the last mentioned notch to raise slide 36 the distance of one tooth as will be readily seen by comparing Figs. 5 and 6, the slide 36 being retained in its new position by pawl 37. This raising of slide 36 results in notch N⁷ being positioned opposite notch N² and thus prepares the way for a further upward shifting of slide 36 in response to operation of pushbutton B and its slide actuating element 40 from the position shown in Fig. 6 to the position shown in Fig. 7. During this operation of pushbutton B the lateral projection 60 of the associated slide actuating element 40 passes from notch N² into notch N⁷ and acts against the top of notch N⁷ to raise slide 36 to the position shown in Fig. 7. In this last mentioned position of slide 36 notch N¹⁰ is positioned opposite notch N⁵ to prepare the way for a further elevation of slide 36 in response to operation of pushbutton E and its associated slide actuating element 40 from the position shown in Fig. 7 to the position shown in Fig. 8. During this operation of pushbutton E the projection 60 of the associated element 40 passes from notch N⁵ into notch N¹⁰ and acts against the top of notch N¹⁰ to raise the slide to a position (Fig. 8) in which the shoulder 52 engages lever 35. Notch N⁹ is thus positioned opposite notch N⁴ so that pushbutton D may be operated a second time to cause the lateral projection 60 of the attached slide actuating element 40 to pass from notch N⁴ into notch N⁹ and to act against the top of notch N⁹ to raise the slide 36 to the position shown in Fig. 9, thus causing shoulder 52 to swing lever 35 in a direction to raise locking pin 19 clear of the tail extension 17 of bolt 10, and permit inward opening of door 5.

In connection with the foregoing description it will be understood that, after each operation thereof, the pushbuttons and their associated slide actuating elements 40 are automatically returned to their starting positions by the springs

65.

Fig. 10 illustrates the manner in which slide 39 is operated to a pawl releasing position to effect resetting of slide 36 and thereby prevent unlocking of the door when the pushbuttons are operated in incorrect sequence. Fig. 10 applies to the case where, through error or lack of knowledge of the correct combination, the operator correctly operates pushbuttons D and B in the

order named and then erroneously operates the button D a second time instead of operating button E as prescribed by the correct combination. In this case inward movement of button D results in the projection 60 of the associated element 40 riding up on the adjacent straight edge of slide 36 and acting against the top of notch N⁴ to raise slide 39 relative to slide 36. This upward movement of slide 39 swings pawl 37 to an inoperative position clear of the teeth 38 of slide 36 with the result that slide 36 drops down by gravity or otherwise to its starting position. This releasement of pawl 37 and resetting of slide 36 will occur whenever the operator incorrectly pushes 15 a button to operate a slide actuating projection 60 which is trapped in a notch of slide 39 by an opposing straight edge portion of slide 36.

In connection with the foregoing description of the pushbutton-controlled combination type door 20 unlocking mechanism it will be understood that the predetermined sequence in which the controlling pushbuttons must be operated to unlock the door is a variable factor determined by the number and relative arrangement of the notches of the slides 36 and 39 and/or the number of pushbuttons provided for operating associated slide actuating elements 40. Accordingly, it will be understood that the slides 36 and 39 shown in the present drawings may be replaced by slides having a different number or arrangement of notches requiring a different sequential operation of the pushbuttons to unlock the door. It will also be understood that the number of pushbuttons employed is a variable factor.

It is also pointed out that the assembly of the slides 36 and 39, the pawl 37, the slide actuating elements 40 and the controlling pushbuttons 41 may be used in various ways for controlling the unlocking of a door. For example, in the case of a door lock including a sliding locking bolt of the spring projected type the slide 36 may be used to operate a suitable bolt retracting lever replacing the locking pin releasing lever 35.

In the case of a sliding door locking bolt which is spring projected, it is difficult to guard against the possibility of the bolt being retracted to a door unlocking position by insertion of some implement between the door and the door jamb. This method of releasement of the bolt cannot, 45 however, be successfully practiced in the case of the jaw type locking bolt previously described herein since the locking bolt is held against swinging movement in one direction about its pivot 13 by the door jamb and against swinging movement in the opposite direction by the locking pin 19.

As shown in Fig. 1, the door carried parts of the lock are concealed at the inner side of the door by a suitably shaped cover plate 67.

Having thus described the nature of my invention and the preferred embodiment thereof, it will be understood that various modifications other than those specifically mentioned herein may be resorted to within the scope and spirit 55 of the invention as defined by the appended claims.

I claim:

1. In a door locking mechanism, a vertically movable bolt controlling slide adapted to be raised in a step-by-step manner from a starting position to an elevated bolt releasing or retracting position, a retaining pawl arranged to engage and support said slide in each of several different elevated positions to which the slide is 70 shifted by successive upward movements thereof,

75

a series of pushbuttons, slide actuating members connected to said pushbuttons and cooperating with portions of said slide to effect a step-by-step raising of the slide to said bolt releasing or retracting position in response to successive operation of certain of said pushbuttons in a predetermined sequence and means functioning, in response to operation of said pushbuttons in other than said predetermined sequence, to shift said pawl out of supporting engagement with said slide, said last mentioned means comprising a second pawl-releasing slide which is actuated to a pawl-releasing position by the slide actuating member connected to the pushbutton which is operated out of proper sequence.

2. In a door locking mechanism, a vertically movable bolt controlling slide adapted to be raised in a step-by-step manner from a starting position to an elevated bolt releasing or retracting position, a slide retaining member normally arranged to engage and support the bolt releasing slide in each of different elevated positions to which said slide is raised by successive upward movements, a second slide for releasing said slide retaining member to permit the bolt-controlling slide to drop back to its starting position, a series of manually movable operating members and slide actuating elements connected to said operating members and cooperating with portions of said slides to (a) effect a step-by-step raising of the bolt controlling slide to a bolt releasing or retracting position in response to successive operation of certain of said operating members in a predetermined sequence; or (b) raise the second slide in response to operation of the operating members in other than said predetermined sequence to thereby cause the said slide retaining member to be shifted out of supporting engagement with the bolt controlling slide.

3. Locking mechanism as set forth in claim 2, in which the two slides are arranged in abutting edge-to-edge relation and have their abutting edges provided with notches constituting the portions of the slides which cooperate with the slide actuating elements.

4. In a door locking mechanism, a vertically movable bolt controlling slide adapted to be raised in a step-by-step manner from a starting position to an elevated bolt releasing or retracting position, a slide retaining member normally arranged to engage and support the bolt releasing slide in each of different elevated positions to which said slide is raised by successive upward movements, a second slide movable independently of the bolt controlling slide and engageable with said slide retaining member to shift the latter out of supporting engagement with the bolt controlling slide, the arrangement being such that the bolt controlling slide is free to drop back to its starting position whenever the slide retaining member is shifted out of supporting engagement therewith by movement of the second slide, a series of manually movable operating members and slide actuating members connected to said operating members and cooperating with portions of the bolt controlling slide to effect a step-by-step raising of the bolt controlling slide to a bolt releasing or retracting position in response to successive operation of the operating members in a predetermined sequence and means whereby the second slide is raised to shift the slide retaining member out of supporting engagement with the bolt controlling slide in response to operation of said operating members in other than said predetermined sequence.
